UNITED STATES PATENT OFFICE.

WILLIS W. SMITH, OF ARKANSAS CITY, KANSAS.

FLUSH-VALVE.

No. 921,017.

Specification of Letters Patent.

Patented May 11, 1909.

Application filed March 18, 1908. Serial No. 421,893.

To all whom it may concern:

Be it known that I, WILLIS W. SMITH, citizen of the United States, residing at Arkansas City, in the county of Cowley and State of 5 Kansas, have invented certain new and useful Improvements in Flush-Valves, of which the following is a specification.

The present invention relates to an improved flush valve embodying novel means 10 for controlling the movements of the valve and timing the same.

The object of the invention is to provide a valve of this character which comprises few and simple parts in its construction and operates automatically to retard the closing of 15 the valve until it is nearly seated, when it is released so as to drop suddenly upon its seat. For a full understanding of the invention and the merits thereof and also to acquire a 20 knowledge of the details of construction and the means for effecting the result, reference is to be had to the following description and accompanying drawings, in which:

Figure 1 is a vertical sectional view through 25 a flush valve embodying the invention the same being shown in a closed position. Fig. 2 is a similar view with the valve in an open position. Fig. 3 is a top plan view of the air cylinder, the screws passing therethrough being shown in section.

Corresponding and like parts are referred to in the following description and indicated in all the views of the drawings by the same reference characters.

Referring to the drawing, the numeral 1 35 designates the valve casing which communicates at its upper end with the lateral branch 2 of the feed pipe 3, the lower end of the valve casing communicating at one side 40 thereof with the flush pipe 4. Extending transversely across the valve casing 1 is a partition or diaphragm 5 formed with a valve seat upon which an upwardly opening valve 6 normally rests, the said valve being held in a closed position by the pressure of the water 45 in the supply pipe.

Extending downwardly from the valve 6 is a stem 7 which passes through a packing box 8 at the bottom of the valve casing and 50 is loosely connected to one end of an operating lever 9. This lever is pivotally mounted at an intermediate point upon an arm 10 which is pendent from the lateral branch 2 of the supply pipe and has its extremity pivoted to a collar 11 fitted upon the said branch 55 of the feed pipe. The opposite end of the

operating lever has a chain or cable 12 connected thereto by means of which the same can be drawn downwardly to lift the valve 6 from its seat, and the swinging movement 60 of the lever is limited by a stop 13 carried by a collar fitted upon the feed pipe. This end of the operating lever is also connected to an upwardly extending link 14 pendent from the piston rod 15 of a piston 16 operating 65 within an upright air cylinder 17. In the present instance this cylinder is shown as carried by collars which are applied to the feed pipe 3. A central opening is formed in the piston 16 and an upwardly opening valve 70 18 is applied to this opening, the said valve being formed with a pendent guide stem 18^a which passes through the opening. It will thus be apparent that when the piston 16 is drawn downwardly the valve 18 will be lifted 75 from its seat and will permit a free passage of air from the lower end of the cylinder to the upper end thereof. However, upon the upward movement of the piston the valve 18 is forced upon its seat and the air 80 above the piston must be forced through a vent opening in the upper end of the cylinder, the effective size of the vent opening being controlled by a screw 19. When this screw has been adjusted to decrease the size 85 of the vent opening a comparatively long time will be required for the escape of the air, while in a reverse manner when the effective size of the vent has been enlarged the air will escape in a comparatively short interval of 90 time.

In order to operate the flush valve it is merely necessary to pull downwardly upon the cable or chain 12, the valve 6 being thereby lifted from its seat and the piston 16 95 drawn downwardly within the cylinder 17. Upon releasing this cable the flow of water through the valve casing 1 tends to force the valve 6 back upon its seat and to move the piston 16 upwardly within the air cylinder. 100 The time required for this upward movement of the piston is controlled by the effective size of the vent opening in the cylinder and may be regulated as desired.

The invention also contemplates means 105 for releasing the valve 6 when the same is nearly closed so that the same will be suddenly and accurately seated, and for this purpose the lower edges of the valve 18 are beveled at 20 and a pin 21 is provided for co-operation with these beveled edges to tilt the valve and open the same at the proper time. 110

2
This pin 21 is shown as threaded in the upper end of the air cylinder 17 and can be moved in and out so as to tilt the valve at the proper time when the upward movement of the piston brings the valve into contact therewith.

Having thus described the invention, what is claimed as new is:

1. The combination of a flush valve, a lever pivotally mounted at an intermediate point and having an operative connection at one end thereof with the flush valve, an air cylinder having a vent in the end thereof, a piston mounted within the air cylinder and having an opening therein, connecting means between the piston and the opposite end of the lever, the said piston coöperating with the lever to retard the closing of the flush valve during a portion of its movement, a valve for the opening in the piston, the edge 15 of the valve being beveled, and a pin for engaging the beveled edge of the piston valve to tilt the valve at a predetermined time and release the flush valve to permit a sudden seating of the latter.
- 20 2. The combination of a flush valve, a feed

pipe formed with a lateral branch pipe leading to the flush valve, a swinging arm pend- 30 ent from the lateral branch of the supply pipe, an operating lever pivotally connected between its ends to the swinging arm, one end of the operating lever being connected to the flush valve, an air cylinder supported by the feed pipe and having a vent in the end thereof, a piston operating within the air cylinder and having an opening therein, 35 connecting means between the piston and the opposite end of the operating lever, the said piston coöperating with the lever to retard the closing of the flush-valve during a portion of its movement, a valve for the 40 opening in the piston, and means for opening the valve at a predetermined point in the movement of the piston to release the flush valve and permit a sudden seating thereof.

In testimony whereof I affix my signature 45 in presence of two witnesses.
